UNITED STATES PATENT OFFICE.

EMANUEL MENDELS AND ABRAHAM MENDELS, OF BALTIMORE, MARYLAND; SAID ABRAHAM MENDELS ADMINISTRATOR OF SAID EMANUEL MENDELS, DECEASED.

DRESS.

1,068,688.

Specification of Letters Patent. Patented July 29, 1913.

Application filed June 13, 1912. Serial No. 703,402.

To all whom it may concern:

Be it known that we, EMANUEL MENDELS and ABRAHAM MENDELS, citizens of the United States of America, residing at the 5 city of Baltimore, State of Maryland, have invented certain new and useful Improvements in Dresses, of which the following is a specification.

This invention relates to a one-piece garment or house-dress, and particularly to the means for fastening the same whereby the garment is quickly and conveniently closed and fastened, and the waistline is at the same time adjusted to exactly the length 15 desired.

Various wrappers and kimonos, intended for the general purpose to which the article of my invention is applied, are in common use. Some of these are loose robes which 20 are cumbersome and otherwise inconvenient when worn by an active person, while others, which fit more closely, are of a fixed dimension when closed and must be made or altered to fit the person who is to wear 25 them. Also putting on and taking off these latter garments consume a considerable amount of time because of the complicated fastening means.

The garment of our invention is made in 30 a single piece, open at the front for its entire length and having relatively wide front flaps. Encircling the waistline is a belt, provided near its ends with a series of fastening means. These are on the outside of 35 the garment, spaced along the belt, and at the opposite side near the back a strap is secured to the inner face of the garment at or near the belt. This strap is provided with a fastener or a series of fasteners adapted 40 to coöperate with those on the belt. At the end of the belt or on the outer edge of the front flap, is another fastening device for securing the front flap when lapped over 45 on the outside. This may be in the form of an invisible hook or eye, and on the outside of the other flap, spaced well back from the edge, there is a corresponding and coöperating fastening member or series of fastening members, as invisible eyes, to coöperate 50 with the fasteners at the end of the belt. For these hooks and eyes any suitable fastening for holding the outside front flap may be substituted.

In the preferred form of our device the 55 garment is made with two front flaps, either

of which may be folded over the other when the garment is closed. At each end of the belt, on the outside, is a cover flap attached at its upper edge to the upper edge of the belt and swinging free. Fastening means 60 are arranged along the belt at each end beneath the flap. There is a strap at each side near the back having corresponding fastening means, and each front flap is provided at its edge with a fastening device, and there is a corresponding fastening or series of fastenings spaced well back from the edge on the outside of each front flap to coöperate with the edge fastening.

In the drawing I have illustrated a garment constructed in accordance with the preferred form of our invention.

Figures 1 and 2 are elevations of the garment in closed position. In Fig. 1 the left front flap is outside and in Fig. 2 the front flap on the right is folded over the 75 left front flap. Fig. 3 is a fragmentary elevation of the garment open and suspended from two points at its upper edge.

The garment, as shown, consists of the 80 usual body portion 1, shaped in a general way to the form of the wearer, being somewhat reduced at the waist, open at the front at 2, from top to bottom, and having front flaps 3 and 4 of considerable width so that 85 when the garment is closed, they lap over for several inches at the waist and to a greater extent below. A belt 5 encircles the waistline, extending from the outer edge of one front flap to the outer edge of the other 90 front flap, and preferably the top of the dress is formed of one piece, gathered in at the bottom and secured to the belt, the skirt being formed of a separate piece and secured at its top edge to the belt. The belt, 95 as shown, is formed with a cover flap 6 at each end, which is secured at the top edge but free at the bottom and front end edges so as to form a depending flap which swings 100 from the top edge of the belt. To form this 100 flap the outer belt strap 7 is utilized, this strap being preferably secured to the belt at its top edge throughout its entire length and at its bottom edge throughout the greater portion of its length, the bottom edge being 105 left free near the ends to form the flap. Beneath the flap 6 at each end is a series of fastenings 8, shown in the form of the well-known ball and socket clasp, though any other fastening may be used. These are 110

outwardly disposed and spaced in the direction of the length of the belt.

Secured to the inner face of the garment at each side near the back, preferably on the belt line, is a strap 9, the straps being fastened at one end and the full length of the strap swinging free. Each strap is provided with one or more fastening members 10 to coöperate with the fastenings 8 on the belt. When a number of fastenings 10 are used, these are spaced in the direction of the length of the strap. Each front flap is provided at or near its outer edge 11 with a fastening member 12. This is preferably 15 at the end of the belt as shown. On the outer face of each flap, spaced well back from the edge and preferably on the belt, is a series of fastenings 13 to coöperate with the fastenings 12. For the fastening devices 12 and 13 we find it most desirable to use hooks at 12 and invisible eyes at 13.

In the operation of the device, one front flap is first drawn forward and laid in position about the wearer. The opposite strap 25 9 is then drawn over to meet the front flap and a fastening 10 thereof brought into engagement with the corresponding fastening 8 beneath the cover flap 6 on the belt portion of the first front flap, the strap being 30 drawn to the desired tension and the corresponding fastenings being chosen with this end in view. The cover flap 6 is then folded down over the strap. The edge of the other front flap is then drawn over the one 35 first operated, and the fastening member 12 is brought into engagement with the corresponding member of the series of fastenings 13.

We have thus produced a house-dress 40 which may be quickly put on or off, and which readily and almost automatically fits itself to the wearer. It can thus be produced in large quantities at low cost and in standard sizes to fit all purchasers.

45 It will be apparent that the nature of the fastenings is not a feature of our invention, and that any suitable fastening means may be employed in the place of those which we have shown and described. It will also be 50 apparent that it is unnecessary to provide

two straps 9 and two sets of fastenings 8, but to make the garment in this way increases its life and makes it possible to maintain a fresh appearance of the garment for a longer period after laundrying, as first 55 one flap and then the other may be worn outside.

We have thus described our invention specifically in order that the nature and operation of the device may be clearly understood. However, the specific terms herein are used in their descriptive rather than in their limiting sense and the scope of the invention is defined in the claims.

We claim—

1. A one-piece garment open at the front for its full length and having front flaps adapted to lap over with either flap outside when the garment is closed, a belt encircling the waistline, cover flaps extending along the belt near each end, fastening means beneath the cover flaps, straps, one attached at one end to the inner face of the garment at each side near the back, a series of fastening means on each strap adapted to coöperate with the fastening means on the belt, and spaced in the direction of the length of the strap, and means for fastening the outer front flap.

2. A one-piece garment, open at the front 80 for the full length and having front flaps adapted to lap over with either flap outside when the garment is closed, a belt encircling the waistline, fastening means arranged along the belt near each end, straps attached 85 by the end, one to the inner face of the garment at each side near the back, and fastening means on each strap adapted to coöperate with the fastening means on the belt and spaced in the direction of the length of the 90 strap, and means for fastening the edge of the outer front flap.

Signed by me at Baltimore Maryland this 7th day of June 1912.

EMANUEL MENDELS.
ABRAHAM MENDELS.
